ARRANGEMENT IN STEAM-ENGINES FOR TAKING WORKING STEAM FROM THE ENGINE-CYLINDERS.

1,142,370.

Specification of Letters Patent.

Patented June 8, 1915.

Application filed April 5, 1912. Serial No. 688,645.

To all whom it may concern:

Be it known that I, WILHELM SCHMIDT, a subject of the King of Prussia, Emperor of Germany, residing at Wilhelmshöhe, near 5 Cassel, Germany, have invented certain new and useful Improvements in Arrangement in Steam-Engines for Taking Working Steam from the Engine-Cylinders for power and other purposes, of which the following 10 is a specification.

My invention relates to arrangements in steam engines for taking working steam, to be used for motors and other purposes, from engine cylinders, and comprises means for 15 controlling both the admission of the working steam into a steam conduit leading from the cylinder wall or cylinder head and the passage of said steam through said conduit. The action of said means, so far as the first 20 named purpose is concerned, is dependent upon the steam pressure existing in the cylinder; accordingly said means are adapted to establish communication between the cylinder interior and the steam conduit, when 25 the expansion pressure has reached a certain definite value and to cut off said communication when the expansion pressure has undergone a predetermined change. I prefer to use for accomplishing said first named purpose 30 a loaded valve opening into the cylinder and for accomplishing the latter purpose a back pressure valve opening into the power pipe, but it should be understood, that other arrangements could easily be effected 35 by those skilled in the art without departing from the scope of the invention.

The object of my invention is to provide a simple and effective arrangement of the character specified which shall be suitable 40 for steam engines of the usual counterflow type as well as for uni-directional flow steam engines. In the prior art such devices have included the placing of a back pressure valve of known type in a definite position in 45 the cylinder wall, said valve being adapted to open as soon as the piston has passed this position, and to close when the expansion pressure in the cylinder has fallen to the value of that in the steam pipe leading from 50 said valve. Since the steam pressure in the cylinder varies with the amount of steam in the cylinder when the piston reaches the valve, so also will the steam in the steam

pipe vary in pressure in this arrangement. With a very small steam cut-off, the valve 55 may possibly not open at all. In the arrangement of my invention, on the contrary, there is complete independence both of the cut-off and of the movement of the piston. The valve always opens at a definite 60 expansion pressure and it can be inserted at any convenient place in the cylinder wall or in the cylinder head. This last feature is especially advantageous when it is desired that only the piston itself shall be 65 lubricated and not the steam, for oil-free steam is, in this way, produced for the motor or heating arrangement.

Referring to the drawings, Figure 1 shows schematically an engine cylinder equipped 70 with my improvement, Fig. 2 shows a central longitudinal section, on an enlarged scale, of the improvement proper; Fig. 3 shows a part of Fig. 2 on an enlarged scale; and Fig. 4 shows the application of my 75 improvement to each end of an engine cylinder.

In the drawings, a steam cylinder *a* is provided with a piston *b* and a cylinder head *c*. An opening *d* in the lower part of the 80 cylinder head co-operates with a valve casing *e* fixed to the cylinder head and provided with an annular channel *g* adapted to open into a steam conduit *f* which I shall, hereafter, call a "power pipe". On the side 85 opening into the power pipe *f* this annular channel is closed by a back pressure valve *h* and upon its opposite side it opens through the opening *d* into the cylinder by a valve *i* the spindle of which carries at its opposite 90 end a small piston *j* adapted to slide in a chamber *k*, *k'*. A spring *l*, which is held in compression between the piston *j* and a pressure plate *m*, tends to keep the valve *i* normally open. The pressure of spring *l* may 95 be regulated by use of the screw *n* which bears upon the outer side of plate *m*. The outer end of chamber *k* is open to the atmosphere at *o*. A tube *p* extends, from a channel *p'* which opens into the inner end of chamber *k'*, outside the cylinder *a* and opens into the remote end thereof at *q*. At the end of this tube *p*, where it opens into the channel *p'*, is placed a back pressure valve *r* adapted to be opened, against the resistance 100 of a spring *s*, into said channel. Even when

this valve r is closed, permanent communication is maintained between tube p and the chamber k' by means of a small notch r' (Fig. 3) cut on the face side of the valve.

5 The operation of my invention is as follows: When the piston b is in position shown in Fig. 1, the several valves which have been referred to are closed. Within the cylinder and in the opening d , the pressure is that 10 of the incoming live steam. In the annular canal g , however, the pressure is approximately that which will prevail at the end of the expansion period; for example, in a non-condensing engine, it will be about two atmospheres. In the portion k' of the chamber k , k' , in consequence of the back pressure notch of the valve r , the pressure will be that of the exhaust of the engine (about one atmosphere in non-condensing engine).

15 The pressure which the live steam exercises upon valve i will over-balance the pressure of steam in the annular channel g plus that of the spring l and will keep this valve i closed. When the piston b moves toward 20 the exhaust end of the cylinder and the steam pressure in the cylinder falls as a consequence, the pressure tending to hold valve i closed will become continually smaller until finally said valve will open.

25 The exact time when this opening takes place may be regulated by spring l through the screw n . If it is determined, for example, that the pressure of the steam to be used for power or other purposes is to be 30 about three atmospheres, then spring l will be so adjusted that its pressure exercised upon the piston j will be about in balance with the pressure in the steam cylinder when the latter is about $4\frac{1}{2}$ atmospheres. As soon 35 as the valve i opens, steam will pass from the cylinder a through the annular channel g against the resistance of back pressure valve h into the power pipe f and continue so to pass until the pressure in the cylinder, 40 by reason of the expansion of the steam contained therein, shall fall to the limiting pressure in the power pipe f (in the foregoing case about three atmospheres). At 45 this instant, the back pressure valve h will close and shut off the power pipe f . Meanwhile compression takes place in the other end of the cylinder, and steam will pass through the pipe p and the back pressure valve r into the portion k' of the chamber 50 k , k' . Just before exhaust takes place, the pressure in chamber k' will have become so great that it will overpower the pressure of spring l upon piston j ; as a consequence of 55 this valve i will be closed. During the 60 turn stroke of the engine piston b to the position indicated in Fig. 1, the valve i will remain closed. The cylinder pressure upon this valve i in consequence of compression will become constantly greater, while the 65 pressure in chamber k' acting upon valve i

to keep it closed in consequence of the notch r' in the back pressure valve r , will become slowly but constantly less, until it is the same as the exhaust pressure. As soon as the piston b of the machine reaches the position of Fig. 1, the cycle of operations begins over again.

70 It is obvious that the arrangement as above described may be used at each end of the cylinder instead of only at one end; such a construction is shown in Fig. 4. It is also clear that my invention is not confined to the exact construction shown and described, but may be varied in detail without departing from the spirit of my invention.

75 Having described my invention I claim:

1. Arrangement in steam engines for taking working steam from the engine cylinders comprising a power pipe connecting with the cylinder interior, means for automatically controlling communication between the cylinder interior and the power pipe, and means for automatically controlling the passage of steam through said 80 power pipe.

85 2. Arrangement in steam engines for taking working steam from the engine cylinders comprising a power pipe connecting with the cylinder interior, a valve adapted to establish and cut off communication between the cylinder interior and the power pipe, both said actions of the valve being dependent upon the pressure in the cylinder interior, and means for actuating said valve 90 to open the power pipe into the cylinder.

95 3. Arrangement in steam engines for taking working steam from the engine cylinders comprising a power pipe connecting with the cylinder interior, a valve adapted to establish and cut off communication between the cylinder interior and the power pipe, both said actions being dependent upon the pressure in the cylinder interior, means for actuating said valve to open the power pipe 100 into the cylinder and means for automatically controlling the passage through said power pipe.

105 4. Arrangement in steam engines for taking working steam from the engine cylinders comprising a power pipe connecting with the cylinder interior, a valve adapted to establish and cut off communication between the cylinder interior and the power pipe, and means for controlling the passage through 110 said power pipe adapted to keep the passage closed during a part of the period of communication established by the valve between the power pipe and the cylinder interior.

120 5. Arrangement in steam engines for taking working steam from the engine cylinders, comprising a power pipe connecting with the cylinder interior, a valve adapted to establish and cut off communication between the cylinder interior and the power pipe 125

130

- pipe, means for actuating said valve to open the power pipe into the cylinder when the expansion pressure in the cylinder has reached a predetermined value, means for closing the valve when the expansion pressure in the cylinder has undergone a predetermined change and means for controlling the passage through said power pipe. 5
6. Arrangement in steam engines for taking working steam from the engine cylinders comprising a power pipe connecting with the cylinder interior, a valve adapted to establish and cut off communication between the cylinder interior and the power pipe, means for actuating said valve to open the power pipe into the cylinder when the expansion pressure in the cylinder has reached a predetermined value, means for closing the valve when the expansion pressure has undergone a predetermined change and means for controlling the passage through said power pipe adapted to keep the passage closed during a part of the period of communication established between the power pipe and the cylinder interior. 10
7. Arrangement in steam engines for taking working steam from the engine cylinders comprising a power pipe connecting with the cylinder interior, a valve adapted to establish and cut off communication between the cylinder interior and the power pipe, and adapted further to directly receive pressure from the cylinder interior for keeping the valve closed during admission of steam into the cylinder, means for actuating said valve to open the power pipe into the cylinder and means to impart pressure to the valve independently of the first-named pressure. 15
8. Arrangement in steam engines for taking working steam from the engine cylinders comprising a power pipe connecting with the cylinder interior, a valve adapted to establish and cut off communication between the cylinder interior and the power pipe, and adapted further to directly receive pressure from the cylinder interior for keeping the valve closed during admission of steam into the cylinder, means for actuating the valve to open the power pipe into the cylinder when the expansion pressure in the cylinder has reached a predetermined value, means to impart pressure to the valve independently of the first named pressure and means for controlling the passage through said power pipe. 20
9. Arrangement in steam engines for taking working steam from the engine cylinders comprising a power pipe connecting with the cylinder interior, a valve adapted to establish and cut off communication between the cylinder interior and the power pipe, and adapted further to directly receive pressure from the cylinder interior for keeping the valve closed during admission of steam into the cylinder, means for actuating the valve to open the power pipe into the cylinder when the expansion pressure in the cylinder has reached a predetermined value, means to impart pressure to the valve independently of the first-named pressure and means for controlling the passage through said power pipe. 25
- to open the power pipe into the cylinder when the expansion pressure in the cylinder has reached a predetermined value, means to impart pressure to the valve independently of the first-named pressure and means for controlling the passage through said power pipe adapted to keep the passage closed during a part of the period of communication established by the valve between the power pipe and the cylinder interior. 30
10. Arrangement in steam engines for taking working steam from the engine cylinders comprising a power pipe, a valve in said power pipe, means for regulating the opening and means for regulating the closing movement of said valve according to the expansion pressures in the cylinder. 35
11. Arrangement in steam engines for taking working steam from the engine cylinder comprising a channel in the cylinder wall connecting with the cylinder interior, a power pipe attached to said cylinder and connecting with the channel, a valve controlling the inlet into said channel from the cylinder interior and a valve controlling the outlet of said channel into the power pipe. 40
12. Arrangement in steam engines for taking working steam from the engine cylinders comprising a power pipe connecting with the interior of the cylinder and a pair of loaded valves in the power pipe for controlling independently of one another the passage of steam through said power pipe. 45
13. Arrangement in steam engines for taking working steam from the engine cylinders comprising a power pipe connecting with the interior of the cylinder and a pair of loaded valves for controlling independently of one another the passage of steam through said power pipe, one of said valves adapted to open into the cylinder and the other into the power pipe. 50
14. Arrangement in steam engines for taking working steam from the engine cylinder comprising a channel in the cylinder wall connecting with the cylinder interior, a power pipe attached to said cylinder and connecting with the channel, a valve controlling the inlet into said channel from the cylinder interior, means for loading the valve, means for regulating said loading, and a valve adapted to control the opening into and passage of steam through the power pipe. 55
15. Arrangement in steam engines for taking working steam from the engine cylinders comprising a channel in the cylinder wall, a power pipe connecting with the channel, a loaded valve in the channel adapted to open into the cylinder, a loaded valve adapted to open into the power pipe and means for regulating the loading of said first named valve. 60
16. Arrangement in steam engines for taking working steam from the engine cylinder. 65

ders comprising a passage in the cylinder wall, a power pipe connecting with the channel, a loaded valve in the channel adapted to open into the cylinder, a valve piston connected to said valve, a back pressure valve adapted to open into the power pipe and means for regulating the loading of said first-named valve.

17. Arrangement in steam engines for
10 taking working steam from steam engine cylinders comprising a channel in the cylinder wall, a power pipe connecting with the channel, a loaded valve in said channel adapted to open into the cylinder, a valve
15 piston connected to said valve and adapted to receive pressure from the other side of the engine piston, a back pressure valve adapted to open into the power pipe and to keep the passage through the power pipe closed during
20 a part of the period in which the first named valve is held open, and means for regulating the loading of said first named valve.

18. Arrangement in steam engines for
25 taking working steam from the engine cylinders comprising a channel in the cylinder wall, connecting with one cylinder end, a power pipe connecting with said channel, a valve in the channel adapted to open into
30 the cylinder by the pressure of a spring, a valve piston connected to said valve, a chamber for said valve piston, a tube connecting said chamber with the other cylinder end whereby pressure is transmitted to the valve
35 piston to close the valve when the expansion pressure in the cylinder has undergone a predetermined change, a back pressure valve adapted to open into the power pipe and to keep the passage through the power pipe
40 closed during a part of the period in which the first named valve is opened and means for regulating the pressure of the spring of said first named valve.

19. Arrangement in steam engines for
45 taking working steam from the engine cylinders comprising a channel arranged in one

cylinder end connecting with the cylinder interior, a power pipe connecting with the channel, a valve adapted to open into the cylinder, a valve piston connected to said 50 valve, a chamber for said valve piston, a spring exerting pressure onto the one side of the valve piston for opening the valve when the pressure of the expanding steam has reached a predetermined value, means for 55 regulating the pressure of the spring, a tube connecting the piston chamber with the other cylinder end whereby pressure is transmitted to the other side of the valve piston for closing the valve when the expanding pressure in the cylinder has undergone a predetermined value, means for controlling the opening of said tube, and a back pressure valve adapted to open into the power pipe. 60

20. Arrangement in steam engines for taking working steam from steam engine cylinders comprising a channel arranged in one cylinder end and connecting with the cylinder interior, a power pipe connecting 70 with said channel, a valve adapted to open into the cylinder, a valve piston connected to said valve, a chamber for said valve piston, a spring exerting pressure on the one side of the valve piston for opening the 75 valve, means for regulating the pressure of the spring, a tube connecting the piston chamber with the other cylinder end whereby pressure is transmitted to the other side of the valve piston, a valve in said tube provided with a notch, and a back pressure valve adapted to open into the power pipe and be closed by the pressure existing in said power pipe. 80

In testimony whereof I have hereunto set 85 my hand in the presence of two subscribing witnesses.

WILHELM SCHMIDT.
